UNITED STATES PATENT OFFICE.

WILLIAM L. MORRIS, OF FORT WAYNE, INDIANA, ASSIGNOR TO S. F. BOWSER & COMPANY, INC., OF FORT WAYNE, INDIANA, A CORPORATION OF INDIANA.

ENGINE OIL CONNECTION.

1,157,894.

Specification of Letters Patent. Patented Oct. 26, 1915.

Application filed February 16, 1912. Serial No. 677,995.

To all whom it may concern:

Be it known that I, WILLIAM L. MORRIS, a citizen of the United States, residing at Fort Wayne, in the county of Allen and State of Indiana, have invented certain new and useful Improvements in Engine Oil Connections, of which the following is a specification.

The invention relates to feed connections 10 in systems for supplying lubricating oil to engine bearings.

The object is to provide an improved construction and arrangement of engine lubricating oil connections, whereby the same is 15 rendered more efficient, and more easily maintained in a condition for normal operation.

A further object is to provide an improved construction and arrangement of engine oil connections and fittings whereby the 20 same may be easily and positively cleaned out without interfering with the running of the engine.

To attain these ends and to accomplish 25 certain other new and useful objects, the invention consists in the features of novelty hereinafter described, shown in the accompanying drawings forming a part of the specification, and finally pointed out more 30 specifically in the appended claims.

In the said drawings, Figure 1 is a perspective view of an engine, to which my improved oiling device is shown applied. Fig. 2 is a view of a portion of an engine showing 35 the application of the improved oiling connections to the connecting rod bearing at the crank shaft end. Figs. 3 to 5 inclusive illustrate various forms of supports by which the oil headers and mains are attached to various parts of the engine to be lubricated. Figs. 6 to 9 inclusive illustrate the details of construction of three way 40 blow-off valve positioned at a right angle turn in the header conveniently arranged for cleaning obstructions from the header. Figs. 10 and 11 illustrate the details of construction of the preferred form of angle valve for use with brass or copper tubing, Fig. 10 being in section; and Fig. 12 illustrates a form of angle valve adapted for use 45 with iron tubing.

In the exemplification of the invention illustrated, the oil main leading from any suitable source of oil supply not shown, is 50 indicated by the reference character 10, and lubricating oil may be supplied thereto from a tank by gravity or any other suitable means. Preferably the main 10 is merely a branch leading from a main supply pipe, particularly where there are a number of 55 engines in any one immediate locality to be lubricated. The oil main 10 is controlled by a valve indicated at 11, which may be of any desired construction, but since the main 10 lies preferably below the bed plate of the 60 engine as shown, the bed plate being indicated by the reference character 12, a valve operating wheel as indicated at 13, secured to the upper extremity of valve stem 14, is mounted in the stand 15 and operatively 65 connected with valve 11, for the purpose of opening and closing it. By means of the valve 11 oil is simultaneously admitted to the two branches 16, 17, the first of which 70 leads to a header 18, from which branches extend to the chief moving parts of the engine to be lubricated, except the out-board bearing which is supplied from the branch pipe 17. The feed pipes 16, 17 are both 75 valve controlled, as by the hand-operated valves indicated at 19, 20 respectively. Beyond the valve 19 the feed pipe, which extends upwardly to the header 18, connects with the rearward extremity of the header, 80 the pipe of the same entering a T fitting, one 85 branch of which is in communication with the header 18 extending over the top of the crank case. The other branch of the T fitting, which fitting is indicated by the reference character 20, may be closed with a suitable cap or plug but which is preferably removable in order that a short pipe 21 may 90 be connected therewith, which pipe is connected at its other end to angle valve 22, into which is adapted to be screwed or otherwise secured the depending feed pipe 23 of a reservoir 24, the purpose of which will be 95 hereinafter described. The header 18 is secured to the cross head casing of the engine, indicated by the reference character 25, by 100 suitable clips which may be formed as shown in detail in Fig. 4, and consisting of a member 26 provided at one end with an eye through which the pipe 18 may be passed and being screw-threaded for attachment to a similarly threaded fastening member 27, 105 which is secured to the cross-head casing 25 by screws as illustrated in Fig. 4, or other suitable means. From the header 18 branch oil pipes extend to all the principal bearings of the engine except the out board bearing. The pipes 28, 29 extend to the eccen-

tric valve rocker bearings, the feed pipe 30 extending to the cross-head lubricator, the feed pipes 31, 32 extending to the governor bearings, the branch feed pipe 32^a leading 5 to the lubricating device for the main crank shaft bearing, and the feed pipes 33 to 36 inclusive leading from the header 18 to the main crank shaft and eccentric bearings, the first two of said pipes feeding the main 10 crank shaft bearing and the last two supplying the eccentric bearings.

The details of arrangement of the oil header and supply pipes will of course vary with the size and organization of the machine to be lubricated, and the engine to 15 which the invention is shown applied is merely one example of a common form of steam engine in which the main bed plate is indicated as stated by the reference character 12, the cylinder by 37, the governor by the reference character 38, the casing covering the eccentric at 39, and the crank shaft at 40. The out-board bearing support is indicated by the reference character 41, and the bearing itself at 42. Beyond the valve 20^a and connected therewith is supply pipe 43, from which lead the branch pipes 44, 45 to the out-board bearing.

It has been heretofore proposed to run 50 lines for feeding oil up to where they branch and to place a cross or T joint in place of an L joint, two openings in the cross being plugged and one in the T joint. Under such conditions, if the lines become blocked they 55 could be shut off at the engine oil stop valve, as for example, the valve 11 or the valves 19 and 20^a, as shown in the present drawings. This would enable the lines to be cleaned by running a wire through the pipes, but provides for only a partial cleaning and much 60 oil is usually spilled around and wasted in doing so. The present invention permits of different methods throughout. Primarily the system consists of a $\frac{3}{4}$ inch oil header, 65 which is the size preferred and shown, although any other desired size of header may be employed. This header is provided with a stop valve as the valve 11 in the branch oil main 10, or either of the stop valves 19 or 70 20, which control the oil systems, fed by oil passing through each of the last mentioned valves. The header 18 beyond the stop valve 19 is provided with a valve at or near the other extremity thereof, as for example, the 75 3-way valve indicated by the reference character 50, which reference character refers to the casing of the valve shown in detail in Figs. 6 to 9 inclusive. The valve casing 50 is provided with the valve member 80 51, having three way passages therein, and being provided with the valve stem 52 and hand wheel 53, by which the valve member 51 may be positioned as in Fig. 9 to direct oil only through the header, which is the position in which the valve normally operates,

with the branch closed. In case it is desired to blow oil through that portion of the header between the stop valve 19 and the valve 50, the valve member 51 may be positioned as in Fig. 7. The valve member 51 70 75 may be positioned so as to direct into the crank pit, the eccentric oil guard, or as illustrated in the present embodiment of the invention, to be discharged laterally and horizontally striking the inside edge of the crank wheel 40^a, from which the oil will be discharged downwardly into the drip pan 54 and out through the discharge duct 55 and oil conducting pipe 56 to any suitable means for the deposit of the waste oil, as for example, to a filter, not herein shown and forming no part of the present invention, but through which the oil may be passed in a well known manner and purified to be afterward returned to the system. 80 85

In equipping an engine with my improved oil connections, the header consisting of that portion of the pipe indicated by the reference characters 16, 18 and 43 may be either formed of iron pipe or of brass pipe. If brass 90 pipe be used it is necessary that an angle valve of the type shown in Fig. 10 be employed, in which view the header pipe is indicated by the reference character 18, and is provided on the upper side of the pipe with 95 an opening as 18^a leading into the casing of the angle valve fitting, which casing is indicated by the reference character 57. Fitting 57 is provided with a valve member as indicated at 59 and a branch opening 58 leading 100 to the opening 18^a along the top side of the header 18 which is closed by the valve 59, having valve stem 60 and hand wheel 61, the entrance of the valve stem to the chamber 58 being closed by the packing gland 62. For 105 the branches leading from the header, as the branches indicated by the reference characters 16, 28, 29, 30, 31, 32, 32^a, 33 to 36 inclusive, and 44 and 45, it is preferred that copper be used as it is capable of standing the 110 bell mouth or expanding of the ends and the making of the short bends necessary in many of the connections. In the form of angle valve adapted for use on brass header pipes 18, as shown in Fig. 10, also in Fig. 11, 115 there is attached to the same a piece of bell mouth copper tubing, which is indicated by the reference character 63, which is of the form as any of the copper tubes of the branch connection leading directly from the 120 bearings of the header. The manner of securing the joint between the copper branch pipes and the angle valve casing is shown in detail, the bell mouth portion of the tube 63 being indicated at 63^a, the same impinging 125 between the conically formed threaded nipple on the valve chamber 57 and the threaded clamping nut 64. The copper branches are secured to the form of angle valve adapted for use with iron pipe as illustrated in 130

Fig. 12, in the same manner as with the angle valve shown in Fig. 10, and the same reference characters are employed to designate the parts in that illustration. The form of valve, however, is different for to the iron header pipe, as indicated also by the reference character 18, the angle valve is secured by having the lower nipple on the casting, indicated by the reference character 65, 10 screwed into an opening on the upper side iron pipe 18. A header pipe constructed of iron will be of sufficient thickness and strength to stand the tapping and threading. The angle valve casing 65 is provided with a 15 valve chamber, from which a passage 66 leads through the nipple to communicate with the opening in the header pipe 18, this opening being closed by a valve 67 similar to the valve 59 carried by stem 68 screw- 20 threaded for adjustment in the valve casing 65 and secured in position by a packing gland, the nut of which is indicated at 69, and the hand wheel for operating the valve at 70.

If an engine is practically free from polished work, painted iron headers would be most suitable. If lubricator cups and other parts show a tendency of brass finish, then the header and oil lines should be polished brass, but if all these parts are nickel plated, 30 then the oil headers and branches should be nickel plated also, the header of brass and the branches of copper. For the out-board bearing at the upper extremity of the header member 43, it is preferred that a cap be provided as indicated at 75, which may be removed after the closing of the stop valve 20^a to clean the branch 43 with a wire, or when the cap be removed an L-shaped piece of pipe may be attached so that the oil may be 40 discharged into a pail or other receptacle.

An important feature of the present invention is that it is so arranged that the oil headers and the branches can be cleaned while the engine is in operation without 45 interfering with the continuous feeding of lubricant to the various bearings, which is an important consideration. If cups at the extremities of the branch feed pipes immediately leading to the various bearings be 50 of the combined pipe and hand feed type, sometimes called pressure cups, as illustrated immediately over the bearings at the extremities of branch feed pipes 33 to 36 inclusive, and 44 and 45, for example, any of 55 the branch feed pipes may be shut off for cleaning and oil supplied through these hand-fed cups until the particular branch or branches shut off be again placed in condition for normal use. The time required 60 for cleaning any branch will ordinarily not exceed one filling of the cup. However, in the event that feeds be provided which do not contain reservoirs for any considerable quantity or supply of lubricant, then it will 65 be necessary to provide means for admitting

oil to each series of branch feeder pipes, which series would be shut off with the same stop valve. I show such an arrangement in connection with my system, illustrated in Fig. 1, all of the branch feeding pipes leading from the header 18 being under the control of the stop valve 19. The T fitting 20 at the upper extremity of the feeding pipe 16 may be provided with a removable plug, screw-threaded and not shown, and when 70 it is desired to shut off the system beyond the stop valve 19 for the purpose of cleaning or repairing the pipes leading to this portion of the system, the T connection 20 may have the plug removed therefrom and 75 a reservoir connected to the same by means of a short section of pipe 21 threaded at one extremity into an angle valve 22, and screw-threaded at one end into the T connection 20. The angle valve 22 may be in communication 80 with a discharge spout 23 of reservoir 24 of funnel form as illustrated, and after stop valve 19 be closed oil may be admitted 85 to the system beyond the stop valve 19 from the reservoir 24 as desired. The reservoir 90 24 will of course be positioned so that oil may reach all parts of the system by gravity. When the system is used in connection with the form illustrated in Fig. 1, it will not be necessary to have the reservoir more 95 than about twelve inches above the level of the main portion of the header 18.

In Fig. 3 there is shown a form of base clip indicated by the reference character 70, adapted to secure the branch feed pipes 100 to various parts of the engine, as for example, to the main crank shaft bearing and the casing over the eccentric. It is desirable that the header pipe 18 be supported some distance from the engine parts and for 105 this purpose I show two forms of specially designed supports, one of which is described in connection with Fig. 4, and the other of which is illustrated in Fig. 5, the latter being particularly designed to support the 110 angular branch of the header 18 adjacent the main crank shaft bearing and consisting of a casting 72 adapted to be secured by suitable screws to portions of the engine, and being provided with a threaded nipple adapted 115 to receive the interior of the threaded end of a section of pipe 73 cut off to any desired length, the other end of which is likewise interiorly threaded and adapted to receive a threaded nipple on the end of an 120 eye 74 adapted to surround the header pipe 18.

It is important that the branches leading directly from the header to the various cups and portions to be lubricated should be supplied with unions at each end so that they may be readily detached for cleaning purposes. The header of the oil main should have a valve at each branch so each particular branch can be removed either to 125 130

clean the same or to get it out of the way of other parts that may require disconnecting while the engine is in operation.

In order to avoid the possibility of accumulation of foreign materials and ingredients that sometimes are found in lubricating materials which may clog and stop the flow, it is desirable that the oil mains and the header in particular should have smooth bottoms along as much of their length as possible, and it is to provide particularly an oil header with branches leading therefrom in which there will be no obstruction to the flow of the oil along the bottom side of the pipes that is one of the principal objects of the invention. It is also found that screw fittings and nipples placed in line, particularly in assembling the branch pipes, are not desirable, as the threads may not be entirely uniform on the ends of the pipe which will result in various sections of the pipes being out of alinement when assembled and hence disfiguring the appearance of the system. To this end the features shown in Figs. 10, 11 and 12 are particularly desirable, since it enables me to employ a header of a continuous section of tubing, as when brass tubing is employed with the fittings shown in Figs. 10, and 11 the fitting may be soldered around the pipe, and when iron header tubing is employed as in Fig. 12 the pipe may be tapped and the fitting attached without cutting the pipe. Thus it will be seen that when fittings of the type shown in Figs. 10 to 12 are employed for connecting the branch pipes with the header the number of joints in the pipe will be greatly reduced in each installation. In some cases where my improved system has been applied to engines of the type similar to that illustrated herein, it has been found that the number of joints in the pipe has been reduced to about one-tenth that was formerly necessary where systems were installed with the ordinary threaded forms of fittings. The necessity for reducing the number of joints as much as possible on account of clogging of joints and leakage has already been explained and will be obvious to those skilled in the art.

In order that the invention might be understood the details of the preferred embodiment have been shown and described, but it is not desired to be limited to the exact details, for it will be apparent that those skilled in the art may resort to modifications and various adaptations of the invention without departing from the purpose and spirit thereof.

60 What I claim is:

1. The combination in a lubricating system for supplying lubricant to a machine, of a pipe line or header adapted to furnish

oil to the machine from a common source of supply, an angle valve casing adapted to be secured to the said pipe line or header adjacent an opening in the upper side in the said pipe line or header, the said angle valve casing being provided with a chamber and an opening leading from the chamber to the pipe line or header opening, means for controlling the chamber opening of the valve casing, and means for attaching thereto a branch feeder pipe adapted to lead to the part to be lubricated. 75

2. The combination in a lubricating system adapted to supply lubricant to a machine, of a pipe line or header for supplying lubricant from a source of supply, a valve for closing the pipe line or header to the source of supply, means for affording access to the interior of the pipe line or header for the purpose of cleaning same, and a portable detachable device for supplying the said pipe line or header with an auxiliary feed of lubricant, said device comprising a container, an outlet pipe or duct for said container, means for securing the outlet pipe or duct to the pipe line or header for admitting lubricant therefrom into the header, and a valve for controlling the passage in the said outlet pipe line or duct.

3. The combination with a supply main for conducting lubricating oil, of conveyer outlets leading therefrom to journals, said conveyer outlets being taken from said main at a point away from its bottom, the bottom of said main being continuous and unbroken past said conveyer outlets, a drip return system for delivering oil back to the lubricating oil supply main, and a blow-off at the end of the said main beyond the outlets to said journals, said blow-off discharging into said drip return system. 95

4. The combination with a supply main for conducting lubricating oil, conveyer outlets to journals being taken from said main at a point remote from its bottom, each of said conveyer outlets to journals having a valve at said supply main with a removable connection between the journals and supply main, the bottom of said main being continuous and unbroken past said conveyer outlets, a drip return system which delivers oil back to the said supply main, and a blow-off at the end of said main beyond the conveyer outlets to said journals, said blow-off discharging into said drip return system. 10

In testimony whereof I have signed my name to this specification, in the presence of two subscribing witnesses, on this 26th day of December, A. D. 1911.

WILLIAM L. MORRIS.
